Primary Examiner — Calvin E Vansant*Assistant Examiner* — Pia J Marchetti(74) *Attorney, Agent, or Firm* — Birchwood IP(57) **CLAIM**

The ornamental design for a car roof bracket, as shown and described.

DESCRIPTION

FIG. 1 is a front, right and top perspective view of a car roof bracket, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion 9 shown in FIG. 1

The broken lines shown in the drawings illustrate portions of the car roof bracket that form no part of the claimed design. The dash dot broken lines in FIGS. 1 and 9 are for the purpose of annotating the enlarged view only and form no part of the claimed design.

1 Claim, 9 Drawing Sheets(56)
